United States Patent Office

Des. 176,946
Patented Feb. 21, 1956

176,946

CONSOLE

Herbert J. Hampel, Philadelphia, Pa.

Application November 30, 1954, Serial No. 33,336

Term of patent 14 years

(Cl. D26—5)

Fig. 1

Fig. 2

Fig. 3

Fig. 1 is a front perspective view of a console showing my new design;

Fig. 2 is a top plan view of the console; and

Fig. 3 is a side elevation of the console.

I claim:

The ornamental design for a console, substantially as shown.
